UNITED STATES PATENT OFFICE

VERNE R. SHATTUCK, OF PITTSBURGH, PENNSYLVANIA

REVERSIBLE SLIP SHEETER

Application filed November 5, 1928. Serial No. 317,233.

My invention relates to improvements in reversible slip sheeter and it more especially consists of the features pointed out in the annexed claims.

5 The purpose of my invention is to provide a slip sheeting device which utilizes a pair of rolls that receive a web of porous material, such as paper, etc.; that as the web is wound on one roll printed sheets are at the same time 10 wound in it, as the web is unwound from the second roll; that simultaneous with the winding up of freshly printed sheets onto the first roll previously printed and blotted sheets are delivered from the second roll; that utilizes 15 an idler roller near the duplicator over which the web passes in traversing from one roll to the other; that provides a horizontal delivery table associated with the idler roller whereby both may be swung on a horizontal plane as a 20 unit so as to be moved away from within the fold of the web; that supports the two paper rolls in a single frame forming a reel rotatable approximately on a horizontal axis in a second frame so that the two rolls may be 25 transposed in position, the one for the other; that makes provision for rotating the second frame approximately on a vertical axis so as to form a turntable for the rolls, thus presenting the opposite roll faces to the duplicator; that releasably holds the several frames 30 in a fixed relation to a main supporting frame; and that by reason of the several co-operating parts makes it possible to simultaneously load one roll while the other roll is 35 being unloaded.

With these and other ends in view, I illustrate in the accompanying drawing such instances of adaptation as will disclose the broad underlying features of my invention 40 without limiting myself to the specific details shown thereon and described herein.

Figure 1 is a side elevation partly in section.

45 Fig. 2 is a front elevation of Fig. 1, showing the web omitted from between the rolls.

Fig. 3 is a plan view partly in section of Fig. 1.

50 Fig. 4 is a diagrammatic view showing the web stretched taut between the two rolls.

Fig. 5 is a diagrammatic view showing the rolls of Fig. 4 inverted.

Fig. 6 is a diagrammatic view showing the rolls of Fig. 5 reversed.

In practically carrying out my invention I 55 may use whatever alternatives of construction that the exigencies of varying conditions may demand without departing from the broad spirit of my invention.

In the main the structure simply comprises 60 a vertical frame joined to a horizontal frame which positions the device in tandem with any desired form of duplicator. The main frame comprises two vertical standards 25 joined at the top by a cross member 24 and at the bottom by a cross member 26. The horizontal frame is formed with two members 17 each one being attached to a vertical member 25 and at their outer end adjacent the duplicator they are joined by a cross member 19. 65

At the bottom end of the vertical members 25 castings 37 may be attached. These castings hold adjustable legs 38 by means of which the vertical position of the frame 17 may be adjusted to the height of the duplicator table 36. Near the outer ends of the members 17 angle brackets 20 may be placed by means of which or otherwise the device may be held in fixed relation to the duplicator. 75

On the frame 17 an idler roller 10 and a 80 receiving table 15 are positioned. Both may be swung horizontally as a unit on pivot 12 supported on a bracket 13. The pivot 12 has an extension 11, as shown in Fig. 3, which extends transversely of the frame 17. This extension has upwardly projecting bearings 43 for the idler roller 10 and two upwardly projecting brackets 14 for supporting the receiving table 15. This table may have sides 44 if desired. 85

The extension 11 has a downwardly extending projection 41 which abuts the cross member 19 and thus serves as a stop and the extension is held in place, as shown in Fig. 3, by a pin 42 or otherwise. The idler roller 10 and the receiving table 15 are swung horizontally on the pivot 12, as shown by the dotted curved lines on Fig. 3, so as to leave the web 9 free to be pulled taut between the two rolls, as shown in Fig. 4, when the lower roll is unloaded 95 100

ready to have the rolls inverted and reversed.

The two storing rolls, shown in Figs. 1 and 2 comprise an upper roll 5 supported on a spindle 7, and a lower roll 6 supported on a spindle 8. The spindles or shafts 7 and 8 have bearing in a unitary frame 28. This frame is pivoted at 29 in a second unitary frame 30, and the latter is pivoted at 33 respectively to the upper member 24 and the lower member 26 of the main frame. The frame 28 may be called the reel, and the frame 30 with its end members 31 may be designated the turn table.

Pins 32 extending between the frames 28 and 30 serve to hold the frame 28 in vertical alignment, and a pin 34 passing through the main frame upper member 24 into holes 35 of the upper cross member 31 serves to hold the turn table in proper position so that the web 9 will move straight between the rolls and over the idler roller 10. Each of the rolls are provided with heads 27. As shown in Figs. 1 and 2 the upper roll 5 has a grooved sheave 4 attached to the shaft 7 on which a belt 3 is placed. This belt drives the roller 5 from a pulley or grooved sheave 2 rotating with the duplicator 1 which may be driven in any suitable manner.

The belt 3 may be tightened when needed by an idler 22 supported on a bracket 21 which is attached to a standard 18 that is supported on one of the members 17. The lower roll 6, shown in Fig. 2, has a driving pulley 23 attached to its shaft 8. The pulley 23 when the reel 28 is turned on its bearings 29, will be in a new position with the roll 6 at the top and the roll 5 will be at the bottom. This will leave the taut side of the web 9 facing the duplicator as shown in Fig. 3 in an inoperative position.

To bring the two rolls into an operative relation to the duplicator a turn table 30 is rotated on bearings 33 so as to position the taut portion of the web away from the duplicator, as shown in Fig. 6. While so positioned the web is pulled out as shown by dotted lines in Fig. 6, and the idler 10 and table 15 are swung laterally into position between its fold. In this position the empty roller 6 will be driven by the belt 3 over pulley 23 in the direction of the arrow, thus loading the roll 6 while the roll 5 is being unloaded. The blotted sheets drop into the tray 40 removably supported on a bench 39. The bench may be positioned in respect of the main frame by means of blocks 16, shown in Fig. 3.

The operation of this device is very simple and can be readily understood from the description and the drawing. As rapidly as the printed sheets are delivered from the duplicator to the web 9 they are wound up in the upper roll and while so wound are being blotted. The accumulated sheets in the lower roll are being delivered to the receiving tray 40. When the lower roll is entirely emptied the

belt 3 is removed from either pulley 4 or 23, whichever one happens to be uppermost, the idler roller 10, is swung to one side so that the slack of the web 9 can be taken up on either one of the rolls bringing it taut on the side of the rolls away from the duplicator. The reel is then turned on its axis and locked to the turntable 30 thus transposing the two rolls, and the turntable is rotatated on its axis and locked so as to bring the taut side of the web 9 away from the duplicator. Then the web 9 is pulled out with sufficient slack to pass over the side boards 44 of the table 15 and over the idler roller 10, after which the driving belt 3 is placed on the pulley attached to the shaft of the empty roll now at the top, which on being rotated becomes loaded, and at the same time through the pulling of the web by this roll the lower one is continuously unloaded.

What I claim is:

1. In slip sheeting devices, a suitable frame positioned adjacent a duplicator, an idler roller supported by the frame between the duplicator and a pair of paper holding rolls, a unitary frame in which the rolls have bearing in parallel relation with each other, a second unitary frame in which the roller frame is pivoted for rotation, a main frame in which the secondary or turn table frame is pivoted for rotation at approximately right angles to the first unitary frame, a web of porous material engaging the idler roller and the two rolls, and means for imparting movement to the web so as to wind up on one roll and unwind from the other the winding roll being loaded and the unwinding roll being unloaded.

2. A slip sheeting device comprising a pair of paper storage rolls, a unitary frame in which the rolls have bearing, a second unitary frame to which the first unitary frame is pivoted, a third frame to which the second unitary frame is pivoted for horizontal rotation, a web of porous paper in operative relation to both rolls, and means for imparting movement to the web.

3. In slip sheeters, a porous web, a pair of rolls for storing the web, means for supporting the rolls in spaced apart parallel relation, means for inverting the rolls with respect to each other, an associated duplicator, means for reversing the inverted rolls with respect to the duplicator, and means for imparting movement to the web and rolls from the duplicator.

4. In slip sheeters, a pair of rolls positioned in spaced apart parallel relation, a porous web, a plurality of cooperating unitary supporting frames for the rolls, means for successively delivering imprinted sheets to one roll, means for inverting one of the frames, means for horizontally rotating said frame by a second frame, and means for imparting movement to the rolls and web.

5. In slip sheeters, a pair of rolls in spaced

apart parallel relation, means for transposing the rolls by inversion, means for reversing the direction the inverted rolls face, a porous web cooperating with the rolls, and means for imparting movement to the rolls and web.

In testimony whereof I affix my signature.
VERNE R. SHATTUCK.
